(57) **CLAIM**

The ornamental design for a grounding clip, as shown and described.

DESCRIPTION

FIG. 1 is a right side perspective view of a first embodiment of a grounding clip;

FIG. 2 is a top plan view of the grounding clip of FIG. 1;

FIG. 3 is a bottom plan view of the grounding clip of FIG. 1;

FIG. 4 is a right side elevational view of the grounding clip of FIG. 1;

FIG. 5 is a left side elevational view of the grounding clip of FIG. 1;

FIG. 6 is a front elevational view of the grounding clip of FIG. 1;

FIG. 7 is a rear elevational view of the grounding clip of FIG. 1;

FIG. 8 is a right side perspective view of a second embodiment of a grounding clip;

FIG. 9 is a top plan view of the grounding clip of FIG. 8;

FIG. 10 is a bottom plan view of the grounding clip of FIG. 8;

FIG. 11 is a right side elevational view of the grounding clip of FIG. 8;

FIG. 12 is a left side elevational view of the grounding clip of FIG. 8;

FIG. 13 is a front elevational view of the grounding clip of FIG. 1; and,

FIG. 14 is a rear elevational view of the grounding clip of FIG. 1.

The broken lines shown represent unclaimed subject matter and form no part of the claimed design.
